LAST

John W. Lefavour, Beverly, Mass., assignor to
 United Shoe Machinery Corporation, Borough
 of Flemington, N. J., a corporation of New Jersey

Application May 3, 1939, Serial No. 271,559

5 Claims. (Cl. 12—136)

This invention relates to lasts and is illustrated herein as embodied in a last by the use of which the delasting of a shoe thereon is facilitated.

The removal of a shoe from a last requires considerable skill and strength on the part of the operator. This is true even in connection with lasts the fore and heel parts of which are relatively movable into a foreshortened relation so as to relieve some of the pressure between the shoe and the last (for example, a hinged last) because at the beginning of the relative movement between the last parts, when the difficulty of moving the shoe with respect to the last is the greatest, the foreshortening effect is slight. 10 This difficulty is aggravated by the fact that the shoe usually affords a poor grip for the operator and is susceptible to damage by abrasion and by straining of the upper or the stitching in it.

In view of the foregoing, it is an object of the invention to provide an improved last having embodied therein, provision for facilitating the separation of the heel part of the shoe from the last by substantially reducing both the amount of effort required heretofore in carrying out this 20 operation and the likelihood of damage to the shoe resulting therefrom.

This object is attained, as herein illustrated, by the provision of means associated with the forepart of a last constructed and arranged to engage the inside of the heel part of a shoe on the last and to press the shoe off the heel part of the last as the fore and heel parts of the last are moved relatively to each other into their foreshortened relation. Thus, with the heel part 30 of the last supported by the usual fixed jack pin the heel part of the shoe is removed from the last while in its normal relation to the forepart by a pressure exerted from within the shoe in response to the foreshortening movement of the forepart thereby largely obviating the practice of pressing on the outside of the shoe upper to remove it from the last and the objections attending this practice.

The above-mentioned means comprises a member which, in accordance with a feature of the invention, is arranged to extend into the heel part, preferably flush with its bottom surface, to a point adjacent to the rear end thereof so that the pressing action of the member will not only be directed against the shoe bottom near the locality where the greatest resistance to the slipping of the shoe on the last is encountered, but also will begin simultaneously with the relative foreshortening movement of 40 the last parts.

These and other features of the invention will appear more fully from the following detailed description when read in connection with the accompanying drawings and will be pointed out in the appended claims. 5

In the drawings,

Fig. 1 is a plan view of a last embodying the invention;

Fig. 2 is a sectional side elevation of the last, its fore and heel parts being in their normal 10 assembled relation, and

Figs. 3 and 4 are sectional side elevations of the last illustrating successive stages in the removal of a shoe from the last, the fore and heel parts of the last being in their foreshortened 15 relation.

The illustrated last comprises a forepart 10 and a heel part 12 arranged to swing on each other between their normal assembled relation as indicated in Fig. 2 and their foreshortened 20 relation as indicated in Fig. 3 on a common form of knuckle joint 14. The fore and heel parts are held together by bonding means comprising links 16 pivoted on a pin 18 mounted in the forepart, a link 20 pivoted on a pin 22 mounted in the 25 heel part and a stud 24 which pivotally connects the links 16 and 20.

The heel part 12 is provided with a recess 26 extending heightwise through the bottom of the heel part and lengthwise thereof from its forward edge rearwardly to a point adjacent to its rear end. This recess is adapted to receive a member 28 mounted on the forepart 10 and extending rearwardly therefrom which, when the last parts are moved into their foreshortened 30 relation, engages the inner surface of the bottom of the heel part of a shoe on the last and holds the heel part of the shoe in its normal relation to the forepart and hence presses the shoe off the heel part of the last, as shown in Fig. 3. 40

The member 28 is pivoted on the pin 18 and is held in its operative relation (Fig. 2) with respect to the forepart 10 by a latch 30 which is pivoted on a pin 32 carried by the forepart and which, by means of a spring 34, is releasably held 45 in a notch 36 in the member 28. A spring 38 mounted in a recess in the forepart 20 is arranged to urge the member 28 toward the heel part 12 against the latch 30. As illustrated in Fig. 2, the part of the member 28 which extends into the 50 heel part 12 is normally flush with the bottom of the heel part and at its rearmost end is provided with an enlargement or pad 40 adapted to engage a substantial area of the inner surface of the shoe bottom. The pad 40 also is adapted 55

to engage and apply pressure to the shoe adjacent to its heel end so as to minimize any binding action between the shoe and the heel part of the last as they are separated.

5 In the use of the illustrated last, the heel part 12 of the last having a shoe thereon is placed upon a fixed jack pin 42 the forepart 10 then being pressed downwardly from its position as indicated in Fig. 2 so as to collapse the last as indicated in Fig. 3. During this movement of the forepart 10 the member 28 is held by the latch 30 in its operative or normal relation with respect to the forepart and presses upwardly against the inner surface of the shoe bottom thereby pressing the shoe off the heel part 12 simultaneously with the foreshortening of the last. Toward the end of this movement of the forepart 10, the lower end of the latch 30 is moved into engagement with the heel part 12, as indicated in Figs. 3 and 4, 10 causing the latch to be swung away from the notch 36. The member 28, under the influence of the spring 38, is then swung in a counterclockwise direction toward the heel part away from the bottom of the shoe so as to avoid obstructing movement of the shoe forwardly of the last off the forepart.

15 It will now be understood that when the forepart 10 is again swung upwardly so as to bring the last parts into their normal assembled relation the latch 30 will become reengaged with the notch 36, the last parts then having the relation in which they are illustrated in Fig. 2.

20 Having thus described my invention, what I claim as new and desire to secure by Letters Patent of the United States is:

25 1. A last comprising fore and heel parts mounted on each other for relative movement between an assembled and a foreshortened relation, the heel part having a recess in its bottom extending lengthwise thereof, and means associated with the forepart and extending rearwardly therefrom into said recess, said means being constructed and arranged to engage the inner surface of the bottom of the heel part of a shoe on the last and to hold the heel part of the shoe in its normal relation to the forepart of the shoe as the last parts are relatively moved into their foreshortened relation.

30 2. A last comprising fore and heel parts mounted on each other for relative movement between an assembled and a foreshortened relation, and

means for pressing the heel part of a shoe on said last off the heel part thereof as the last parts are moved out of their assembled relation, said means comprising a member mounted on the forepart and arranged normally to extend substantially flush with the bottom of the heel part to a point adjacent to the heel end of the last.

35 3. A last comprising fore and heel parts mounted on each other for relative movement between an assembled and a foreshortened relation, the heel part having a recess formed therein and a member disposed in said recess and carried by the forepart, said member having a surface substantially flush with that of the bottom of the heel part, and means for releasably holding said member in the same relation with respect to the forepart as the last parts are moved into their foreshortened relation whereby a shoe on said last is pressed off the heel part thereof.

40 4. A last comprising fore and heel parts mounted on each other for relative movement between an assembled and a foreshortened relation, a member mounted on the forepart in juxtaposition to the inner surface of the bottom of the heel part of a shoe on the last when the parts thereof are in their assembled relation, and means for releasably holding said member in the same relation with respect to the forepart of the last as the last parts are moved into their foreshortened relation, said means being operated by engagement with the heel part to release said member thereby permitting it to be moved away from the shoe.

45 5. A last comprising fore and heel parts mounted on each other for relative movement between an assembled and a foreshortened relation, the heel part having a recess formed therein, a member pivotally mounted on said forepart and normally disposed in said recess, a surface of said member normally being substantially flush with the bottom surface of the heel part, means tending normally to urge said member away from its said normal position toward said heel part, and a latch carried by the forepart for releasably holding said member in the same relation with respect to the forepart as the last parts are moved into their foreshortened relation, said latch being operable to permit said member to be swung by said yielding means toward the heel part of the last.

50 JOHN W. LEFAVOUR.
